UNITED STATES PATENT OFFICE.

EDWIN DRAYTON BELKNAP, OF EAST ORANGE, NEW JERSEY.

SELECTIVE DEVICE FOR CARD-HANDLING APPARATUS.

1,172,862.

Specification of Letters Patent.

Patented Feb. 22, 1916.

Application filed March 2, 1914. Serial No. 822,045.

To all whom it may concern:

Be it known that I, EDWIN DRAYTON BELKNAP, a citizen of the United States of America, residing at East Orange, county of Essex, State of New Jersey, have invented certain new and useful Improvements in Selective Devices for Card-Handling Apparatus, of which the following is a specification.

10 My invention relates generally to apparatus for automatically selecting certain cards from a series of the same and delivering them to a special receptacle, or special compartment of a general receptacle. Its 15 most important application, so far as now known to me, is in the selecting and separating from a series of stencil cards, used in addressing machines by publishers of periodicals, those bearing addresses of subscribers whose subscriptions expire at a certain date or within a certain period. In operating such an apparatus a series of many thousands of stencil cards are fed through a printing apparatus, said cards being arranged in alphabetical order or by geographical classifications, rather than by date of expiration of the subscriptions represented thereby. In is necessary, however, after, or while, the entire list of addresses borne by 20 these cards, has been or is being printed for mailing a given issue of the periodical, to eliminate those cards bearing the addresses of subscribers whose subscriptions expire before the date of issue of the next number 25 of the periodical. My invention accomplishes this result in a positive and efficient manner without defacing or tearing the cards.

The best form of apparatus embodying 30 my invention, at present known to me, is illustrated in the accompanying four sheets of drawing in which—

Figure 1, is a side elevation of the mechanism to be attached to a standard form of 35 addressing machine of the general type such as is shown in Patent No. 976,142, granted to me Nov. 22, 1910, certain parts being broken away. Fig. 1^a, is a detail view in vertical section of certain parts shown in 40 Fig. 1, the selective device being disabled. Fig. 2, is a plan view, with parts broken away. Fig. 3, is a front elevation, with parts broken away or shown in section. Fig. 4, is a detail view, partly in section, showing card guide and selective plunger, with 45 all selective pins removed. Fig. 5, is a vertical section of certain portions of the apparatus on line 5—5 of Fig. 2 and showing certain parts broken away and others in elevation, the selective device being in operation. Fig. 6, is a detail plan view of the selective plunger head with selective pins removed, and Fig. 7, is a similar view of one of the stencil cards used in addressing machines, which card has holes punched in its frame to coöperate with my invention.

Throughout the drawings like reference characters indicate like parts.

1, represents a magazine for the retention of the stencil cards discharged from the addressing machine such as is shown in my prior patent above referred to. The bottom of this magazine is shown broken away but under normal conditions the cards thrust into the magazine from the card guides 3, 3, 70 through the slot 3^a, in the side of the magazine will fall to the bottom of said magazine and there accumulate in a pile.

2, is a movable partition or diaphragm which extends practically entirely across the magazine at right angles to its length and divides the space in said magazine into two separate chambers 46, and 47. When, as is usual, the magazine is vertically arranged, the movable partition 2, is held in a substantially horizontal position as shown in Figs. 1 and 3, dividing the magazine into a lower chamber 47, and an upper chamber 46.

A stencil card 4, of the character with which my invention is designed to coöperate, is shown in Figs. 3 and 7. This card has several holes 5, 5, punched in the sides of its frame, the location of said holes varying according to the different weeks of the year they are designed to represent. As indicated in dotted lines in Fig. 7, the holes may be located in any one of the eight positions indicated on each of the longer sides of the card frame. One hole being punched on each side, it is evident that it is possible 95 to secure sixty-four different combinations of two holes, taking one on each side, which number of combinations will more than take care of the fifty-two weeks of the year. The location of hole 22, in one end of the card frame corresponds to a certain year and as there is provision for three different locations of this hole, as shown in dotted lines, this will take care of subscriptions running for one, two or three years, the usual limit 100 of subscriptions for periodicals.

6, is the head plate of a vertically recipro-

cating plunger slide 9. This head plate 6, has a series of perforations or notches 7, 7, in its sides and in one end corresponding to the possible locations of the holes 5, and 22, in the stencil card.

8, 8, represent two pins which may be fastened in the particular slots on the sides which correspond to the location of two holes in the sides of a card frame which 10 would correspond to a certain week in the year on which the subscriptions represented by the cards which are to be eliminated from the main body of the cards would expire.

39, is a pin inserted and fastened in one 15 of the slots in the end of head 6, and which represents the year of the expiration of such subscription.

The movable partition 2, is preferably supported upon the bellcrank 10, pivoted at 20 11, upon the supporting arm or standard 51, projecting up from the base plate 41, on which the sub-frame 50, supporting the rest of the mechanism also rests. Preferably the movable partition 2, has notches 12, 12, cut 25 in its corners and into these notches extend the bent portions of card supporting springs 13, 13, fastened to the sides of the magazine 1. As shown, these springs are fastened to the exterior of the magazine and have bent 30 portions forming projections 48, with inclined under faces 49, extending through openings in the sides of the magazine into the spaces left by the notches 12, 12. As shown, the upper surfaces of the projections 35 48, are in the same plane as the upper surface of the movable partition 2, or slightly below it. It is evident that a stack of cards in the upper chamber 46, of the magazine will rest on and be supported by the projections 48, 48, of the springs 13, 13, when the latter are in their normal position and that 40 these springs will hold said cards in position even when the movable partition 2, is dropped down into the position shown in 45 dotted lines in Figs. 3 and 5.

14, is a spring also mounted on the magazine and engaging the bellcrank 10, to normally hold it and the movable partition 2, in their upper or horizontal positions, as 50 best shown in Figs. 1 and 3.

The preferred form of mechanism for lowering the movable partition to the position shown in dotted lines in Figs. 3 and 5, comprises a trigger bellcrank 15, pivoted to 55 the sub-frame 50, at 25, and having one extremity connected by link 16, to pivot 26, on the bellcrank 10. The lower end of trigger 15, is located in the line of travel of the lug 18, on the member 17, of the telescoping slide 17-27. The outer end of this 60 member 17, of the telescoping slide engages the slot 20, in the plunger slide 9, and has a shoulder 19, which will engage the said slide 65 when it is in its lower position (see Fig. 1a) but will pass freely into the slot 20, when

the slide 9, is in its uppermost position, as shown in Fig. 5. The two sections 17, and 27, of the telescoping slide are normally held apart and the slide distended by coiled spring 21. Slide section 27, is normally 70 pulled to the right (looking at Figs. 1, and 5) by retracting spring 23, connected to spring peg 24, on the slide section 27, and to the fixed pin 43, in the base plate 41. A cam roller 28, is mounted in the end of slide 75 section 27, and engages cam 30, on cam shaft 29. This cam shaft is mounted in journals 44, on base plate 41, and also carries the V-shaped resetting cam 31, which engages cam roller 32, on the lower end of bellcrank 10. 80 This shaft 29, also carries a cam 36, which I will call the plunger cam, which co-operates with the cam roller 35, on the rear end of plunger lever 33, which is pivoted to the sub-frame 50, at 34. This plunger lever 33, has a pivoted section 37, supported by spring 38. The forward end of this lever 33, engages slot 52, in plunger slide 9. The rear end of the lever 33, and cam roller 35, are forced upward by spring 40. Guides 42, 42, for the plunger slide 9, are formed in the sub-frame 50, and guides 45, 45, are provided for the horizontally reciprocating telescoping slide 17-27.

The mode of operation of my invention is 95 as follows: Assuming that the addressing machine (not shown) is operating to print the addresses from the entire active subscription list for the issue of a weekly periodical dated for the eleventh week of the year, it is desired to separate from the entire body of stencil cards bearing all the addresses on the subscription list, those stencil cards bearing addresses of subscribers whose subscriptions expire immediately 100 after that 11th week of the year and before the next issue. According to my invention all cards bearing such addresses would have holes 5, 5, and 22, punched in them. The holes 5, 5, would represent the eleventh in 110 the series of two hole combinations made possible by taking one hole in each side frame, and the hole 22, would represent the current year. Selective pins 8, 8, would be set in notches 7, 7, of plunger head 6, corresponding to card frame holes 5, 5, and another pin 39, would be set in a notch 7, corresponding to card frame hole 22. As the stencil cards are fed along from the addressing machine through the guides 3, 3, each card 115 stops for a moment (the card feeding action being intermittent) immediately over the reciprocating plunger head 6. While the card is in this position of rest the plunger head is forced up by the conjoint action of cam 36, 120 plunger lever 33, and spring section 37. If the card in the guides over the plunger has perforations 5, 5, and 22, as shown in Fig. 7, the selective pins on the plunger head will enter these openings and the plunger slide 9, 125 130

will have its full upward motion. This will bring the slot 20, in line with the body of section 17, of telescoping slide 17-27, so that when the cam 30, strikes cam roller 28, 5 and pushes the telescoping slide 17-27, to the left, the shoulder 19, will not strike the slide 9, but the section 17, of the telescoping slide will have the full motion which the throw of cam 30, normally gives it. This 10 motion is sufficient to cause the slide lug 18, to strike the trigger bellcrank 15, and pull down the bellcrank 10, and movable partition 2, into the position shown in Fig. 5. This brings the movable partition below the level 15 of card guides 3, 3, and slot 3^a, so that when a resumption of the card feeding movement (after the descent of the plunger slide 9,) forces said card through the slot 3^a into the magazine 1, it will land on top of the movable 20 partition 2. When the cam shaft 29, continuing to rotate in the direction of the arrow, brings the resetting cam 31, into contact with cam roller 32, on the lower end of bell crank 10, and forces the movable 25 partition 2, back to its normal position, shown in Figs. 1 and 3, the card carried by this partition will be forced between the card supporting springs 13, 13, which are forced apart by the cam action of their inclined under faces 49, 49, and the projections 48, 48, thereon will snap in under the card and hold it permanently in the upper chamber 46, of the magazine. If the next card is not one which has holes punched as shown 30 in Fig. 7, the upward thrust of the plunger slide 9, will bring one or more of the selective pins 8, 8, and 39, against an unpunched portion of the card frame and check the movement of said slide before it has risen 35 high enough to clear the shoulder 19, on the telescoping slide section 17. This checking of the motion of the slide 9, is rendered possible by reason of the yielding action of the section 37, and spring 38, carried by 40 plunger lever 33. (See Fig. 1^a.) The result of the holding of the plunger slide 9, in a half raised position will be to similarly check the sliding motion of the section 17, of the telescoping slide before its lug 18, strikes the 45 trigger 15 shoulder 19 on slide 17-27 striking plunger slide 9. Consequently, the movable partition 2, will remain in its normal horizontal position and when a resumption of the card feeding action forces this second 50 card through slot 3^a, into the magazine, it will fall to the bottom of said magazine, remaining in the lower chamber 47. Constant repetition of these two operations above described according to the perforations in the 55 cards being discharged, will cause all of the cards having holes punched in them in the position shown in Fig. 7, to accumulate in the upper chamber 46, the bottom card of the stack resting on the projections 48, 48, of springs 13, 13; while the other cards, rep-

resenting subscriptions not expiring that week, will drop into the main magazine chamber 47. When the addresses for the next issue of the periodical are printed, one of the selective pins 8, will be moved into 70 the next notch 7, and so on each week.

My invention has the advantages among others of positiveness of operation and freedom from any wearing action on the cards, which are not subjected to any further handling or manipulation than would be the case if no selective apparatus were used. 75

It is evident, of course, that many other forms of mechanisms could be devised for producing the relative movements of parts: 80 above described, that other arrangements of magazines and the separating apparatus co-operating therewith could be employed and numerous changes made in the details of construction herein described, without departing from the novel principle of operation of my invention. 85

Having described my invention, I claim:

1. The combination with a magazine for the reception of stencil or other cards having certain diverse classifying characteristics, which magazine is provided with a slot in one side through which the cards may be fed into the magazine, and means for feeding said cards through said slot, of a movable partition in said magazine and mechanism controlled by the distinguishing characteristics of the respective cards for moving said partition to one side or the other side of said slot. 90

2. The combination with a magazine for the reception of stencil or other cards having certain diverse classifying characteristics which magazine is provided with a horizontal slot in one side through which the cards may be fed into the magazine, and means for feeding said cards through said slot, of a horizontally movable partition in said magazine, means for normally holding the same above the level of said slot and 105 means controlled by the distinguishing characteristics of certain cards for temporarily depressing said partition below the level of said slot during the feeding of the card possessing such characteristics through the slot. 110

3. The combination with a magazine for the reception of stencil or other cards having certain diverse classifying characteristics which magazine is provided with a horizontal slot in one side through which the cards may be fed into the magazine, and means for feeding said cards through said slot, of a horizontally movable partition in said magazine, means for normally holding the same above the level of said slot and 115 means controlled by the distinguishing characteristics of certain cards for temporarily depressing said partition below the level of said slot during the feeding of the card possessing such characteristics through the slot. 120

125

130

1 together with resilient devices located in said magazine above the level of the slot for retaining such cards as are lifted to them by the movable partition when returning to 5 its normal position after each temporary depression.

4. The combination with a magazine for the reception of stencil or other cards having certain diverse classifying characteristics which magazine is provided with a horizontal slot in one side through which the cards may be fed into the magazine, and means for feeding said cards through said slot, of a horizontally movable partition in 10 said magazine, means for normally holding the same above the level of said slot and means controlled by the distinguishing characteristics of certain cards for temporarily depressing said partition below the level of 15 said slot during the feeding of the card possessing such characteristics through the slot, together with resilient devices located in said magazine above the level of the slot for retaining such cards as are lifted to them 20 by the movable partition when returning to its normal position after each temporary depression, said partition having notches formed in its edges and said resilient means comprising yielding fingers mounted on the 25 magazine walls, normally projecting into said notches and provided with beveled under faces.

5. In a card selecting apparatus the combination with separating means, of guides 30 along which cards having perforations therethrough are fed, a reciprocating plunger having projections adapted to enter perforations in certain cards, means for forcing said plunger with yielding pressure against 35 each card brought to rest in a certain position in said guides, and mechanism for actuating said separating means comprising a trigger connected to said separating means and a spring distended telescoping slide for 40 operating the trigger, the said reciprocating plunger coöperating with the telescoping slide to telescope and disable the same from 45 action on the trigger when the plunger does not make a full stroke, but permitting the 50 slide to reciprocate freely and engage the trigger when the plunger does make a full stroke.

6. The combination of a guideway, means 55 for feeding a series of cards along said guideway, a plunger movable on lines intersecting the line of card travel in said guideway provided with a selective device adapted to engage said cards consecutively and thereby vary its extent of travel, yielding 60 means tending intermittently to force the plunger and selective device toward the

cards, a slide movable toward and from the plunger, means locking said slide against forward movement when the plunger is in certain positions, but permitting such forward movement when the plunger is in other positions, yielding means tending to move the slide toward the plunger, a movable card directing member located at the delivery end of the card guides, and mechanism for transmitting each forward movement of the slide to said card directing member.

7. The combination of a card guideway, means for feeding cards along the guideway, a magazine at the end of the guideway having a plurality of compartments, means for directing the cards into one or another of said compartments, a plunger movable toward and from the guideway and having a selective device adapted to engage each card opposite it in the guideway, and thereby vary the travel of the plunger, yielding means for moving said plunger to produce said engagement, a slide movable toward and from the plunger, means whereby the movement of said slide is controlled by the position of the plunger, and connections whereby certain movements of said slide are transmitted to the card directing means.

8. The combination of card guideways, a card feeding device, a card directing device at the end of the guideways, a plunger movable at right angles to the guideway provided with selective pins adapted to engage 95 each card when in line with it, said plunger having a transverse opening through it, a slide movable at right angles to the plunger in line with said opening when the plunger is in one position and out of line therewith when the plunger is in other positions, yielding means for moving said plunger toward each card as it comes opposite the selective pins, yielding means for moving the slide toward the plunger each time the selective pins engage a card, and a trigger connected to the card directing device located in the line of travel of the slide, whereby the character of the card engaged by the selective pins determines the extent 100 of motion of the plunger, which determines the extent of motion of the slide by the alignment or non-alignment of the plunger opening with the slide, and determines the engagement or non-engagement of slide and 105 trigger which in turn operates the card directing device.
